[57] CLAIM

The ornamental design for a truck bed roll panel, as shown.

DESCRIPTION

FIG. 1 is a top front perspective view showing our new design for a truck bed roll panel;

FIG. 2 is a top rear perspective thereof;

FIG. 3 is a front elevational view thereof;

FIG. 4 is a rear elevational view thereof;

FIG. 5 is a bottom view in reduced scale thereof; and, FIG. 6 is a side-elevational view thereof in larger scale with the opposite side being a mirror image.
